UNITED STATES PATENT OFFICE.

LONGLEY LEWIS SAGENDORPH, OF PHILADELPHIA, PENNSYLVANIA.

METALLIC ROOFING.

SPECIFICATION forming part of Letters Patent No. 425,830, dated April 15, 1890.

Application filed January 24, 1890. Serial No. 337,952. (No model.)

To all whom it may concern:

Be it known that I, LONGLEY LEWIS SAGENDORPH, a citizen of the United States, residing at Philadelphia, in the county of Philadelphia,

5 State of Pennsylvania, have invented certain new and useful Improvements in Metallic Roofing, of which the following is a specification, reference being had to the accompanying drawings, forming a part thereof.

10 The object of my invention is to provide a simple and effective means for uniting or locking together the sides of metallic roofing-sheets, the means employed being such as that the roofing-sheets may be rolled in a compact form for shipment and the seam-cap formed after having arrived at its destination, as will more fully hereinafter appear.

In the accompanying drawings, Figure 1 is a plan view of the end portion of a roofing-sheet, showing the position of the cleat-openings before the side flange and cap-seam are formed, the dotted lines indicating where the bends are made in the sheet to form said side flange and cap. Fig. 2 is a view similar to Fig. 1, showing the preferred form of cleat in position in the cleat-openings, in which position the roofing-sheets may be rolled for shipment if desired. Fig. 3 is a perspective view of the end portions of two roofing-sheets 25 as placed together before the seam-cap is formed, the dotted lines indicating where the bend will be to form said cap. Fig. 4 is an end view of a roofing-sheet having the side flange and seam-cap formed with a cleat in position in said cap. Fig. 5 is a perspective view of two roofing-sheets in position to be locked, the view being taken from the reverse side of that shown in Fig. 3; and Fig. 6 is a similar view with a portion of the seam-cap folded to place. Fig. 7 is a cross-section through the standing seam, taken between the cleats; and Fig. 8 is a similar view taken through said seam and one of the cleats.

My invention consists in forming near the outer edge of the roofing-sheet and on that side from which the overlapping seam-cap A will be formed the cleat-openings *a*, into which the end portion *b* of the cleat B rests, as shown, the shoulders *b'* of the cleat resting against the metal of the roofing-sheet at each side of said openings. The cleat-openings are formed, preferably, before the seam-

cap A is bent, and the tongues *b* of the cleats B are then put to place, as shown in Fig. 2, in which position the roofing-sheet may be rolled in a compact form for shipment with the cleats in position.

The seam-cap A and flange C of each roofing-sheet may be bent and formed in the factory before shipment, as shown in Fig. 4, or 60 after having been put to place on the roof, as shown in Figs. 3, 5, and 6. In either case the cleats B are bent and formed with the seam-cap A after the tongue *b* of each cleat has been put to place, as shown in Fig. 2. It will 65 be seen that the shoulders *b'* of each cleat fit up against the roofing-sheet at each side the cleat-openings *a*, and that the apex bend of the seam-cap A is formed on a plane below the cleat-openings, (before bending,) as shown 70 in Figs. 3, 5, and 6, and when bent to position the apex of this seam-cap A is on a plane above said openings, as shown in Fig. 4, in which position the shoulders *b'* of each cleat are bent below the apex of the seam-cap. 75

The object in having the seam-cap and cleat bent in such a manner as that the shoulders *b'* of each cleat when bent will fall below the apex plane of the cap is that the cap cannot be elevated to slip or become loosened 80 from the cleat—that is, after the cleat is thus bent and nailed to the sheeting the cap A cannot be elevated, on account of the shoulders formed on each cleat on the inside of the seam-cap. 85

My invention is applied as follows: When the vertical flange C and seam-cap A are formed before leaving the factory, as shown in Fig. 4, the cleats B are nailed to the sheeting, and the flange C of the adjacent sheet is 90 then put to place between the upward and downward bent portions of the cap, the body portion of said adjacent sheet resting on the cleats, in which position the seam-cap and cleats are compressed or pinched together 95 with suitable tools, as shown in Figs. 7 and 8. When thus united, it is impossible for the wind to blow off or loosen the roofing-sheets, for the reason that any upward tendency of the cap A is prevented by reason of the shoulders *b'* on the cleats B. When the sheets and cleats are shipped in a roll and the flanges and seam-caps formed on the roof, as shown 100 in Figs. 3, 5, and 6, the cleats are first bent

outward at an angle and on a plane with the body of the roofing-sheet, (after the vertical portion of the cap is bent as shown,) in which position said cleats are nailed to the sheeting, 5 and the overlapping portion of the seam-cap is formed with suitable tools and compressed over the flange C of the adjacent sheet in the manner aforescribed.

The advantages of my invention are many 10 and apparent. The shoulders formed on the cleat, when applied in the manner just described, afford a simple and secure means to prevent the seam-cap from becoming disengaged from said cleats, and at the same time 15 admit of ample expansion and contraction. The seam-cap thus formed is free of any overlapping outside cleats, which is a great advantage, as all outside cleats are liable to rust or cause the cap-seam at those points to rust and 20 leak. The seam-cap, being free of any overlapping cleats, presents a neater appearance and will last longer. The cleats, being protected by the seam-cap, will last much longer, which renders the connection between the 25 roofing-sheets more secure. A portion of surface metal is dispensed with, lessening the cost of manufacture. The cleats, being bent with the seam-cap, enable the roof to be applied quickly and economically.

What I claim as new, and desire to secure 30 by Letters Patent, is—

1. The means herein shown and described for connecting and anchoring metallic roofing-plates to the sheeting, consisting of a slot formed in the downward extension of the 35 seam-cap and a shouldered cleat, the narrow tongue portion of said cleat resting in said slot and the shoulders of said cleat resting against the roofing-sheet at each side of the said slot as and for the purposes set forth. 40

2. A metallic roofing-sheet having at one side the vertical flange C and at the other side the seam-cap A, the latter having a slot 45 a in its downward extension, in combination with a shouldered cleat B, the tongue portion b of said cleat resting in said slot, the shouldered portions b' b' of said cleat resting against said cap-seam at each side of said slot on the under surface of said cap, as set forth.

3. The metallic roofing-cleat B, having the 50 narrow tongue extension b and shoulders b', said cleat being so bent and formed as that said shoulders will fall below the apex bend thereof, as and for the purposes set forth.

LONGLEY LEWIS SAGENDORPH.
